Des. 239,393
Patented Mar. 30, 1976

239,393

ELECTRONIC REMOTE CONTROL VIDEO PROGRAM SELECTION DEVICE OR SIMILAR ARTICLE

George R. De Land, Yorba Linda, Calif., assignor to
Odetics, Inc., Anaheim, Calif.

Filed June 24, 1974, Ser. No. 482,348

Term of patent 14 years

Int. Cl. D13—03

U.S. Cl. D26—13 C

FIG. 1 is a front perspective view of an electronic remote control video program selection device or similar article showing my new design;

FIG. 2 is a right side elevation view thereof;

FIG. 3 is a rear elevation view thereof; and

FIG. 4 is a rear perspective view thereof.

The bottom of the electronic remote control video program selection device or similar article is planar and unornamented.

I claim:

The ornamental design for an electronic remote control video program selection device or similar article, as shown and described.
